ACTUATING LINKAGE FOR FOLDING DOORS
John C. Young, Reedsville, Pa., assignor to Vertex, Inc.,
a corporation of Pennsylvania
Filed Dec. 7, 1966, Ser. No. 599,847
7 Claims. (Cl. 160—165)

ABSTRACT OF THE DISCLOSURE

The invention is directed to apparatus which is useful for linking door panels together for actuating a folding and unfolding of the panels in a sequential pattern of graduated movements. The apparatus is applicable to folding doors which fold in accordion fashion to be stacked over doorways, and such doors are used in large buildings, garages, and the like. The preferred sequence of movement for opening the door of this invention includes an initial folding of an uppermost pair of panels, which in turn causes graduated folding movements of intermediate pairs of panels and of a lowermost pair of panels. Linkage members are interconnected between edges of the panels, and the linkage members are guided along tracks located in a door frame which assists in the control of the folding sequence of the door panels. Further, the linking members include an uppermost linking arm which automatically swings the uppermost panel of a door assembly out of a vertical position when the assembly is lifted, and this causes a chain-reaction folding of all panels of the door assembly.

Brief description of invention

This invention relates to an improved mechanism for actuating overhead folding doors of the type having a plurality of panels which can be folded relative to one another in an accordion fashion. In particular, the invention relates to an improved linkage mechanism which causes a series of door panels to be sequentially moved into folded and unfolded relationships in accordance with a requirement to open or close a door opening.

Folding doors having a plurality of panels hinged to one another for stacking or folding in an overhead relationship to a door opening are known in the art, and various devices have been utilized for folding and unfolding such doors to effect an opening and closing of a doorway. Prior mechanisms have been relatively complex, and have most often required complex counterweight and spring devices for effecting a proper folding and unfolding of adjacent hinged panels in such door structures. Also, it has been proposed, as shown in the Young et al. Patents 2,952,311 and 2,952,312 to actuate the opening and closing of horizontally sliding doors by means of a lazy tong mechanism which moves adjoining panels into stacked positions at one side of a doorway. Of course, the latter type of construction is quite different from the requirements of an overhead folding door structure, but the sliding door arrangement is mentioned as an indication of prior art attempts to actuate door structures generally. Also, prior art attempts have been largely directed to pivoting door panels about central axes through the lengths of the panels, and no constructions have been successful in providing for a controlled folding of a series

2

of panels about axes along the edges of the panels. The latter arrangement is especially important for overhead door assemblies.

The present invention provides for an improved mechanism which is especially useful for actuating an overhead door structure which is made up of a series of hinged panels which can be stacked in an overhead position relative to a door opening. When it is desired to close and seal off the door opening, the stacked panels are unfolded so as to become coextensively arranged in a vertical plane with no overlapping of adjoining edges of adjoining panels. The actuating mechanism of this invention utilizes a type of lazy tong linkage arrangement, however, the linkages are arranged in a novel manner and in such a way as to result in a novel cam action which determines the sequence of folding and unfolding for a plurality of panels making up a complete door. The linkages of the present invention which are associated with the separate panels of a door are arranged in a modified lazy tong configuration wherein the linkages themselves and the edges of separate door panels make up the configuration. Further, the so-called lazy tong arrangement is such that a true parallelogram configuration is not formed, and therefore it is possible to obtain a continuous and non-overlapping alignment of all of the door panels when they are moved to a position which closes the doorway with which the door panels are associated.

In order to obtain a perfectly straight, and non-overlapping, relationship of adjoining panels when a door assembly is extended to a fully closed position, two separate linear paths of movement are provided along an upright edge of the doorway for separately controlling the folding and unfolding movements of door panels and of linkages associated with the panels. All of the linkage members are guided by a first guiding means for all folding and unfolding movements, and all of the door panels are guided by a second guiding means for the corresponding movements, and the two guiding means are arranged so as to cause a novel action which determines a sequence of folding and unfolding movements for the entire door assembly.

The invention also provides for a novel mechanism associated with an upper panel of a folding door structure wherein the upper panel is initially moved to begin a folding movement for all of the remaining panels of the door assembly. This arrangement permits the door panels of an assembly to be stacked over a doorway in a preferred sequence or rate of folding wherein the uppermost panels are initially folded at a faster rate than the lowermost panels of the assembly. This is a desired arrangement for overhead folding doors, such as might be used as garage doors, because it is preferred to have the lowermost panels remain in a substantially unfolded condition for as long as possible when a door is being lifted for opening so as to avoid interference with nearby objects or persons. Thus, the invention provides for an overhead door actuating mechanism which is safer in its operation, and which, because of its simplicity in construction, is reliable and easily manufactured.

These and other features of the invention will be discussed in detail below with reference to the accompanying drawings in which:

FIGURE 1 is a back plan view of a door assembly in a fully closed position in a doorway wherein the assembly is made up of three pairs of panels hinged together at adjoining edges on horizontal axes;

FIGURE 2 is a side elevational view of the door assembly taken at lines 2—2 of FIGURE 1, and illustrating a linkage mechanism associated with the separate door panels when the door assembly is in a fully extended and closed position;

FIGURE 3 is a similar view to FIGURE 2 and showing the relationships of linkage members and door panels when the door assembly is moved upwardly for a short distance to initiate a folding and stacking of separate panels in an overhead position relative to the doorway;

FIGURE 4 illustrates the fully stacked position for all door panels, and the linking members are shown in greater detail as related to the fully stacked panels;

FIGURE 5 is a horizontal cross section of a double track means associated with the door assembly for guiding and controlling the sequential folding of separate pairs of panels of the assembly;

FIGURE 6 is a detailed illustration of a connection between two linking members when their associated door panels are in fully extended, closed positions;

FIGURE 7 is a similar view to FIGURE 6, but showing the relationship of two linking members when a folding movement of the door panels is initiated;

FIGURE 8 illustrates a further progression from the views of FIGURES 6 and 7; and

FIGURE 9 is a detailed illustration of an actuating arm means associated with the upper end of the door assembly.

Detailed description of invention

Referring to FIGURE 1, a typical door assembly of this invention is illustrated in a fully closed position to cover or seal off a doorway in a building. Such a door assembly may be utilized as an overhead door in a garage, or as an overhead door in any building opening which requires a relatively large doorway to be opened and closed. The door assembly of FIGURE 1 is illustrated as being made up of three pairs of panels 10, 12 and 14, and individual panels are hinged to adjacent panels on horizontal axes by any well-known hinging means such as the hinges 16. The panels are arranged in pairs so that each pair is made up of two single panels having a common hinge axis which permits folding movement of the pair of panels in one direction only, while adjoining pairs of panels have common hinge axes which permit a folding of the adjoining pairs in opposite directions from that permitted for the panels within the first pair. Thus, the panels of the entire assembly are permitted to fold back and forth in a zigzag relationship so that they can be stacked in accordion fashion when they are folded to open the doorway in which they are mounted.

The entire door assembly is positioned between upright jamb members 18 of a doorway, and the assembly is held in position relative to the doorway by upright guiding means which carry roller or bearing devices 20 associated with edges of the separate panels and with linking members 22 of the door assembly. The detailed structure of the guiding means and of the linking members which are controlled thereby will be discussed below, but generally, the linking members function to hold the panels of the door assembly in a desired sequential relationship to one another for all folded and unfolded positions. Also, rollers are associated with the door panels to guide the door assembly within the door opening so as to maintain the door assembly within the doorway.

FIGURES 2 and 3 illustrate side elevational views of linking members 22 which are associated with the edges of separate door panels to control the folding and unfolding of the panels relative to one another when the door assembly is lifted or lowered for opening or closing a doorway. In the illustrations of FIGURES 2 and 3, the panels are shown in full end view so that their upright

edges are seen as related to the linkage members associated with the door assembly. FIGURE 2 shows the door assembly in a fully extended or closed position wherein all separate panels are aligned coextensively with their adjoining edges face to face and without any overlapping between adjoining panels. This type of fully extended relationship is required for relatively large door assemblies which are used to seal buildings, and of course, it is understood that well known sealing means may be utilized in combination with the assembly to provide for a tight closure between adjoining panels and between the assembly and a doorway in which it is installed. FIGURE 2 also illustrates the positions of linking members associated with each panel and with each other in a special arrangement wherein the linking members cooperate with the separate panels to form a modified parallelogram (that is, an untrue parallelogram) configuration when the assembly is seen from a side elevational view. All linking members 22 and 23 are interconnected with each other to form a first zigzag configuration while all door panels are interconnected to form a second zigzag configuration when the assembly is folded. The two configurations are offset from each other and cross one another, as shown, with each linking member 22 being connected at an intermediate point to an edge of a door panel. The linking members 23 are made up of two separate elements which are pivotally connected to each other and to an edge of a door panel, as shown. The relationships between the linking members and the door panels is determined, in part, by separate vertical guide tracks positioned alongside the doorway for receiving roller bearings associated with the linking members and with the door panels. As will be explained, the guide tracks provide separate linear paths of movement for the linking members and for the door panels so as to dictate the separate folding movements of the linking members and of the panels. The illustrated sequence of movement for upper panels as compared to lower panels of a door assembly is preferred for overhead doors which are installed in large buildings or garages and where it is desirable to prevent an extreme folding of lower panels until those panels have moved out of the way into positions above the doorway. Such overhead doors may be manually lifted as by a handle, and alternatively, a lifting mechanism may be provided in the form of a motor with a cable wind-up which serves to apply a lifting force to the door assembly. In either case, it is desirable to minimize outward folding movements of the lowermost panels because such movements would interfere with nearby objects or persons standing near the door assembly. With the graduated sequence illustrated in FIGURE 3, it is apparent that the uppermost panels begin their folding movements before the lower panels begin to fold completely. The graduated sequence continues as the door assembly is lifted for opening, but the lowermost pair of panels 14 catch up with folding positions of the uppermost pair when all panels are related to one another at approximately 90°, and then all panels continue to fold at the same rate until fully stacked.

The initial folding movements are determined by a lifting action on the entire assembly together with a swinging action which is provided by a novel actuating arm 30 associated with the upper panel of the assembly. Referring to FIGURES 4 and 9, the actuating arm is mounted at an upper end of the guide tracks associated with the doorway, and the actuating arm is mounted at 32 to pivot about a fixed axis which will determine the initial movements of the entire assembly. The uppermost panel of the entire assembly carries a sleeve member 34 which is constructed to receive the actuating arm 30. Bearing devices may be included between the actuating arm 30 and the sleeve member 34 to assure an easy sliding movement between the two members, and the sleeve or sliding member is positioned to engage the arm 30 for all open and closed positions of the door assembly. For a six panel door, the sleeve member is rigidly secured to an

edge of the uppermost panel, as shown; but for a five panel door the sleeve member may be pivotally attached to the uppermost panel of the assembly. When the closed door assembly is initially lifted for opening, the top panel carries the sliding member 34 along with it, and the member is thus caused to slide along the actuating arm 30. However, the uppermost panel carries a bearing means 36 at its upper edge and which is located in a track which is offset from the pivotal mounting point of the arm 30, and lifting movements cause the arm to be swung in the direction shown in FIGURES 3 and 9. It will be appreciated that the upward movement of the uppermost panel and its sliding member in the track 42 applies a thrust to the arm 30 so as to pivot it about its fixed mounting point 32. As the entire door assembly continues in its upward lifting movement, the arm 30 likewise continues in its swinging movement until it reaches the nearly horizontal position shown in FIGURE 4. Of course, pivotal movement of the arm 30 carries with it the uppermost panel because of the connection of the sliding member 34 with the arm 30. Thus, the arm 30 functions to initially break the uppermost pair of panels 10 and to begin folding movements for the remaining panels of the door assembly. The arm further functions to continue the folding movement of the upper pair of panels 10 until they are fully folded or stacked relative to one another. The bearing 36 has been described as being guided by a track, and the track may be an extension of a track means associated with all remaining panels of the assembly. Tracks 40 and 42 are arranged along either or both sides of the doorway in which the assembly is installed, and FIGURE 5 illustrates in cross section a typical extrusion for a double track system of the type contemplated by this invention.

When the initial folding movement of the upper pair of panels 10 is initiated, as determined by the actuating arm 30 discussed above, the remaining pairs of panels are caused to begin their respective graduated folding movements from the top to the bottom of the door assembly. The graduated sequence of folding movements for the remaining panels is determined by the novel arrangement of linking members 22 and 23 being guided and controlled to maintain a predetermined relationship between adjoining panels which are being folded or unfolded. As can be seen in FIGURES 2 and 3, each linking member 22 or 23 is mounted to contact one panel of the door assembly and to be pivotally linked with an adjoining linking member. In this sense each linking member 22 and 23 functions as a single member interconnecting adjoining linking members to form a zigzag configuration, however, it is to be understood that the linking members 23 are made up of two elements which are pivotally connected at the point where they are connected to the edge of a door (as illustrated), and this feature permits a limited amount of flexing of the linking members to avoid a binding of the members in their relationship to the door panels. The linking members and door panels connected thereby are arranged in a modified lazy tong configuration wherein linking members 22 and 23 make up one part of the configuration while the door panels themselves make up a second part of the modified lazy tong configuration. When the upper pair of panels 10 begin their folding movement for opening the door assembly, a short linking member 44 is caused to be carried inwardly away from the lower panel of the pair 10 to actuate a linking member 22 which is connected at 46 to the short member 44. The actuated member 22 then carries an upper panel of the pair 12 inwardly away from a vertical plane so as to initiate folding movements for the pair of panels 12 and all remaining panels of the assembly. The actuated linking member 22 is pivotally connected to the upper panel of the pair 12 and is also connected to a lower adjoining linking member 23, as shown. The adjoining linking member 23 also includes a roller bearing at its point of connection 48 with the linking member 22, and

the roller bearing is confined within and guided by the first vertical track 40. This pattern of assembly is continued for the entire door assembly and for as many pairs of panels as may be desired. Each of the panels making up the entire assembly includes at least one edge which is guided by the second track 42 while each of the linking members 23 making up the assembly includes one end portion which is guided by the first track 40. The two tracks 40 and 42 are offset relative to one another and this offset arrangement provides for a novel cam action of the linking members and of the door panels relative to one another. Each set of linking members is made up of one member 22 (formed as a single element) and one member 23 (formed from two elements).

The FIGURES 6 through 8 illustrate a sequence of pivotal movements between adjoining linking members 22 and 23 as a door assembly is moved from a fully closed (unfolded) position to a fully opened (folded or stacked) position. Also, the FIGURES 6 through 8 illustrate a special construction of adjoining linking members 22 and 23 at their points of connection to provide for a limited linear movement of adjoining members in addition to the desired pivotal movement of the members relative to each other. One purpose in providing limited linear movement between linking members is to compensate for a slight expansion of distance between rollers 20 of each pair of panels which takes place when the pairs of panels are moved from fully closed to partially opened positions. The expansion of distance is a result of the hinge axis between each panel of a pair moving through and past the guide track axis for the rollers 20. In the FIGURE 6 view, it can be seen that the linking members 22 and 23 are in nearly vertical positions, and this is the position of adjoining linking members when the door panels of an assembly are in completely vertical and aligned positions. It should be noted that by maintaining the linking members in incomplete alignment when the door is fully closed, the members are in positions for immediate pivotal movements in the proper direction and without any binding when the door is opened. Also, the linking mechanism of this invention provides for a substantial "locking" of all panels absent any vertical movement of the upper pair. The linking members 22 and 23 are interconnected by a connecting pin 50 which is, in turn, connected to a roller or bearing member 20. The roller 20 is of any conventional construction, and may be in the form of a ball bearing having a nylon tire, thus having a relatively low friction mounting on the end of the pin 50. The roller 20 for linking members is carried for vertical movements within the track 40, and of course, it is understood that vertical movements of the roller are determined by forces applied to the linking members 22 and 23. The lower linking member 23 of the two members illustrated in FIGURE 6 includes a point of connection for the pin 50, and the point of connection is a fixed pivotal point for the lower linking member and the pin 50. The upper linking member 22 of the two members illustrated in FIGURE 6 includes an elongate slot 54 which permits the pin 50 to move in a limited linear direction relative to the upper linking member 22. Thus, there is provided a pivotal connection between the two illustrated linking members wherein the point of connection can be moved in a linear direction for a limited distance relative to one of the linking members. The purpose in providing the limited movement between adjoining linking members is to allow for expansion of adjoining door panels in a pair as folding movement progresses from a fully closed to a partially opened position. Also, limited movement between linking members accommodates the offset track arrangement and the non-parallel configuration which is formed as a desired part of this invention. In the position shown in FIGURE 6, the door is in a fully closed position, and no opening movements have been initiated for the panels connected to the illustrated linking members.

FIGURE 7 illustrates the relative positions of a pair of linking members 22 and 23 when their associated panels have begun a folding movement. When a folding movement is initiated for a door assembly, forces are applied to the panels of the assembly in an upward or lifting direction, and thus, the rollers 20 associated with each of the pairs of linking members 22 are moved upwardly as shown by the arrow in FIGURE 7. When an upper panel is initiated for an opening, folding movement, as when the actuating arm 30 is used to initiate the folding of a pair of panels 19, there is a pivotal movement of the associated upper linking member 22 about the axis of the pin 50. This pivotal movement takes place at the same time that the roller 20 is being moved upwardly in the track 49, and if the pivot point of the pin were fixed, the lower adjoining linking member 22 would be folded at the same rate as the upper member. This would be a result of a parallelogram type of linkage between the linking members and the door panels. However, the pivotal connection of the pin 50 between linking members is not fixed, and therefore, the roller 20 does not move upwardly as rapidly as it would with a fixed pivotal connection between the linking members. As is apparent in FIGURES 7 and 8, the roller and pin are permitted to ride downwardly in the elongate slot 54 of the upper linking member 22, and this relative movement between linking members retards the upward rate of movement for any given roller 20. This relationship between linking members causes lower panels of a door assembly to initially fold at a graduated rate and at a rate which is slower than the folding rate of the upper panels. Then, as the pins 50 approach lower limits of the slots 54 the folding rate of the lower panels catches up with the upper panel folding rate. When the pins reach the lower limits of the slots, all panels are in approximate 90° positions relative to one another, and from there, all panels fold at the same rate until stacked. In the final stacked position, all of the folded panels and associated linking members are stacked as shown in FIGURE 4, and that figure also illustrates a typical installation which includes a winding drum 60, under spring tension, and a cable 62 for lifting and balancing the weight of the door panels when the door is to be stacked over a doorway. The drum 60 includes varying diameter cable receiving portions for changing the mechanical advantage of the drum as the door is lifted, and any well known construction may be used for this purpose.

Having described the constructional features of this invention, it is apparent that the improved linking system provides for a novel actuation of a folding door assembly, and the described linking system and actuating means is easily constructed and is reliable in its operation. The linking members may be made of any suitable metal material, and may be in the form of elongate bands of metal which can be overlapped, as shown, or any other suitable means may be utilized for linking adjoining members together. The linking members are illustrated as being pivotally connected to intermediate points of a door, and this connection may be made directly into an exposed edge of the door, or a separate mounting bracket and connection means may be utilized. Also, the actuating arm 30 has been described as being received by a sliding member 34 and this arrangement contemplates a structure wherein the arm may slide within the sliding member, or vice versa.

For heavier doors, a further auxiliary link member 70 may be connected between the two uppermost panels to provide additional strength to the linkage system.

Although the invention has been described with primary emphasis on overhead folding door assemblies, it is contemplated that the described invention may also be used for folding door arrangements wherein separate panels are folded and stacked laterally to one side of a door opening.

Variations in the described structure will become apparent to those skilled in the art, and such variations are

intended to be included within the scope of this invention.

What is claimed is:

1. In a folding overhead door assembly of the type wherein panels are hinged together in pairs for being folded on their hinge axes and wherein adjoining pairs of panels are hinged together to be folded on their hinge axes in opposite directions from the folding of panels within a pair, the improvement in a linking mechanism for controlling the sequence of folding movements for the assembly comprising:
linking members pivotally connected to one another at their ends and including first bearing means at their points of connection for being guided in a first track, said linking members being further pivotally connected at intermediate points along their lengths to separate door panels of the said assembly, the linking members and separate door panels being arranged in separate paths which can be folded in accordion fashion in opposite directions from each other at given levels of the assembly,
second bearing means connected to upper and lower edges of each pair of folding panels for being guided in a second track means,
first and second track means vertically positioned along a doorway in which the assembly is installed, said first and second tracks defining separate parallel paths of movement for said first and second bearing members associated respectively with the linking members and with the panels of the assembly, and
means associated with the pivotal connections of the linking members to each other for permitting a limited linear movement of each linking member relative to an adjoining and connected linking member, whereby when folding movements are initiated in an uppermost pair of panels for the assembly corresponding folding movements for lower pairs of panels are initially started at a graduated and slower rate than for the uppermost pair.
2. The improvement of claim 1 and including an actuating arm means for initiating a folding movement of an upper pair of panels of said assembly when the door is opened, said actuating arm means comprising:
an arm which is connected to a portion of the doorway for fixed pivotal movement relative thereto, the point of pivotal movement being vertically offset from said second track means,
a sliding member fixed to an uppermost panel of the door assembly for engaging and sliding along said arm, and
a roller bearing means connected to an upper edge of said uppermost panel for being guided by said second track and for swinging the arm about said fixed pivotal point when the door assembly is initially lifted for opening the doorway, thereby causing the upper pair of panels to be initially swung into a folding movement when the assembly is lifted.
3. The improvement of claim 1 wherein said last named means comprise elongate slots formed in the ends of certain linking members for receiving a pin means connected to adjoining linking members.
4. The improvement of claim 3 wherein each said pin means is also connected to each of said first bearing means.
5. The improvement of claim 1 wherein said first and second track means are arranged side by side along an upright jamb portion of the doorway.
6. The improvement of claim 1 wherein said linking members comprise relatively flat, elongate members which overlap each other at their points of connection with each other, and wherein the separate linking members are connected to vertical edges of said door panels.
7. The improvement of claim 6 wherein said linking members are made up of sets of two members and wherein each set of linking members includes:
a first linking member made up of a single element

which extends between terminal ends of adjoining linking members, and with a midpoint of said first member pivotally connected to the edge of a door panel,
 a second linking member made up of a pair of elements, with one of said elements extending between an adjoining first linking member and an edge of a door panel, and with a second of said elements further extending between the edge of the door panel and another adjoining linking member.
